UNITED STATES PATENT OFFICE

CHARLES P. EISENHAUER, OF DAYTON, OHIO, ASSIGNOR TO THE DURO COMPANY, OF DAYTON, OHIO, A CORPORATION OF OHIO

ELECTRIC MOTOR

Application filed March 11, 1929. Serial No. 346,100.

My invention relates to propulsion-induction motors, and, in particular, to a cutout mechanism therefor.

It is the object of my invention to provide 5 a centrifugally-operated cutout which is spring resisted in its outward movement.

In particular, it is a feature of my invention 10 to provide a sliding spring-resisted sleeve that not only resists the movement of the contact members but serves to hold them uniformly in engagement with the commutator.

Referring to the drawings:

Figure 1 is a side elevation partially in 15 section showing the parts in position of rest;

Figure 2 is a similar view showing the parts in operation;

Figure 3 is a section on the line 3—3 of 20 Figure 2;

Figure 4 is an end elevation;

Figure 5 is a perspective of one of the contact segments.

Referring to the drawings in detail, 1 is 25 an armature shaft having a commutator 2 mounted thereon. This commutator is provided with an internally-arranged cut away portion or slot 3 with a contact face 4 with which the contact segments 5 engage.

Each of these segments is provided with 30 a head 6, a stem 7 and a foot portion 8 having a heel 9 on which the segment pivots. The toe of this foot portion designated 10 engages with the rear wall of an annular, cup-shaped member 11, one wall of which 12 35 acts as an internal support for the segment maintaining them in alignment while the other wall 13 serves as a base upon which the ring 11 slides on the retaining cup 14 in which the segments pivot. This sliding ring 11 is resisted in its sliding movement 40 by the spring 15, the free end of which rests upon the collar 16.

The retaining cup has a sleeve 17 mounted 45 on the armature shaft 1 that forms the annular sliding support for the cup-shaped member 11. One corner of the bottom of the cup, as at 18, serves as a pivotal point for the rocking of the segments 5.

When the armature shaft gets up its speed, 50 the segments pivot about the center 19 on

the cup 14 until the outer ends 6 engage the surface 4 of the commutator 3. This centrifugal action occurs against the resistance between the toe 10 and the annular member 11 and the spring 15. The advantage of my construction is that I have a single spring of rugged character thoroughly enclosed where dirt cannot prevent its operation.

I have frictional resistance between the annular member 11 and the sleeve 17 in addition to the spring resistance. I provide a support such as the member 11 and its wall 12 that maintains the segments all in predetermined relationship.

This prevents any segments from making contact or breaking contact prematurely ahead of the other segments. It causes the segments to move as a unit. It eliminates the spring which has customarily been placed around such segments. Such a spring, because weaker in one place and stronger in the other would eventually allow some segments to make contact or break contact before the others. It is highly essential in such a construction to provide for a uniform, positive 75 and even operation.

It will be understood that I desire to comprehend within my invention such modifications as may be necessary to adapt it to varying conditions and uses.

Having thus fully described my invention, what I claim as new and desire to secure by Letters Patent, is:

1. In combination, a commutator, a segment supporting cup formed from one piece of sheet metal, a plurality of segments pivoted therein, a segment aligning annular cup slidably mounted within the space inclosed by said segments to maintain them in alignment, and yielding means resting within said annular cup to resist the reciprocation of said annular cup when moved by the segments during the centrifugal operation thereof.

2. In combination, a commutator, a supporting cup for contact segments, a plurality of contact segments comprising a contact head stem and foot, said segments being adapted to be pivoted on the cup on the heel of the segments, said foot resting on the bottom of the cup, and yielding means to resist 100

the pivotal movement of said segments, a sliding spacing member held between the toe of said foot and said yielding means and between the inside of the stem of said segments and an armature shaft supporting said commutator, said cup substantially enclosing said segments, said spacing member and yielding means.

3. In combination, a commutator having an internally disposed contact surface, an armature shaft supporting the commutator, a plurality of contact segments having a contact head, stem and foot, a horizontally disposed supporting cup mounted on said armature shaft, the bottom of the foot of said segments resting on the bottom of the cup, an annular member U-shaped in section, the bottom of which engages the top of said foot and one side of which engages the inner sides of the segment stems and the other side of which is slidably mounted on the inside of the cup adjacent the armature shaft, and yielding means for resisting the movement of said member through the action of the toe of the foot when the contact head is moved outwardly centrifugally.

4. In combination, an armature shaft, an internal cutaway commutator thereon, a plurality of segments having heads adapted to engage said commutator, a supporting cup mounted on said armature shaft in which said segments are pivotally mounted, segments aligning means slidably mounted on the armature shaft supporting the inner sides of said segments and adapted to be moved by said segments when they are centrifugally operated and yielding means for resisting said movement, said supporting cup substantially enclosing said segments and aligning means.

5. In combination, an armature shaft, a commutator thereon having a cutaway portion, a supporting and enclosing cup forming with said cutaway portion a chamber, said cup having an inwardly directed sleeve member engaging said shaft, a plurality of contact segments in said chamber, each contact segment having a head projecting within said cutaway portion adapted to engage said commutator, a stem and a foot-like part engaging said cup for pivotal movement about the heel of said foot-like part, a U-shaped ring having one side engaging the stems of said segments, another side engaging said sleeve and another side engaging the toes of said foot-like parts, and a spring between said ring and said commutator to control the movement of the segments due to the rotation of said shaft.

60 In testimony whereof, I affix my signature.
CHAS. P. EISENHAUER.
